Filed Nov. 28, 1960, Ser. No. 72,066

19 Claims. (Cl. 343—5)

This invention relates to a system of direct labeling of data display information presented on a cathode-ray oscilloscope and, more particularly, to the novel means for the display of established symbols simultaneously with the related data on a cathode-ray tube oscilloscope, the symbols being maintained throughout in constant size, aspect, and rectitude.

Direct labeling of data display information is becoming more essential as system complications increase and resolution time decreases. For example, in an air traffic control radar system for which the present invention was conceived, the simultaneous presentation on a PPI scope of as many as twenty-four airplanes was required. Since the airplanes are constantly changing position, it would be virtually impossible for an operator to keep track of each airplane without some system of identification. By means of this invention, the return signal indication from each airplane is marked by an identifying symbol which constantly follows the indication as it moves about the cathode-ray tube screen; and the symbol is maintained in constant size, aspect, and rectitude.

There are many prior art devices capable of applying an appropriate symbol to a cathode-ray oscilloscope. These include complex function generators and charactrons. Although these work fairly well, they are very complex, resulting in high cost and difficult and expensive installation and maintenance. This invention provides system simplification which results in a considerable reduction in cost and an increase in reliability.

The primary object of this invention is to present established identifying symbols, alpha-numeric or line drawing, adjacent related data indications on a cathode-ray tube.

Another object of this invention is to present established identifying symbols adjacent related data indications on a PPI display and to maintain the symbols at a constant size and rectitude.

Another object of this invention is to present symbols on a PPI scope at a position corresponding to the azimuth and range of a selected target.

Still another object of this invention is to rectilinearly scan a symbol with a beam of light to produce electrical impulses which are applied to the intensity control grid of a PPI oscilloscope, the scanning of the symbol in one direction being synchronized with the radial sweep of the beam of the oscilloscope, said scan being controlled to originate at determined periods, and thereby reproduce the symbol on the oscilloscope.

Another object of this invention is to present on a PPI radar cathode-ray tube identifying symbols adjacent a preselected target by applying, at controlled times to the intensity control grid of the oscilloscope, voltages produced by scanning said symbol with a beam of light in two dimensions, the sweep of said beam in one dimension being in synchronism with the radial sweep of the beam of the cathode-ray tube.

A further object of this invention is to present on a PPI radar cathode-ray tube identifying symbols adjacent a preselected target by applying, at controlled times to the intensity control grid of the oscilloscope, voltages produced by scanning said symbol with a beam of light in two dimensions, the sweep of said beam in one dimension being in synchronism with the radial sweep of the

2

beam of the cathode-ray tube, and rotating the scan of the symbol counter to the PPI sweep in synchronism therewith.

Still another object of this invention is to provide a symbol display system in which symbol size is constant, irrespective of the position of the symbol on the cathode-ray tube.

Another object of this invention is to provide a unique generator capable of producing sawtooth oscillations having constant maximum and minimum values, irrespective of the slope.

For further objects and for a more complete understanding of the operation of this invention, reference should now be made to the accompanying drawings, in

15 which:

FIG. 1 is a diagrammatic representation, partly in block form, of a preferred embodiment of this invention;

FIG. 2 is a diagram illustrating the requirement for aspect ratio correction;

20 FIG. 3 is a circuit diagram showing the range and azimuth scanner trace generators and the aspect ratio correction circuit;

FIG. 4 is a series of curves illustrating the operation of this invention; and

25 FIG. 5 illustrates a modified form of mask useful in this invention.

While it is clear that this invention may be adapted to many other uses, for simplifying the discussion it will be described here in connection with a particular air traffic control system in which the invention was actually reduced to practice. The over-all air traffic control system, which utilizes PPI radar apparatus, is capable of automatically tracking, scheduling, and issuing orders for controlling the altitude and heading of aircraft so that they will arrive at selected intervals at the entry point of a landing system (G.C.A., I.L.S., etc.) in line with the runway and at a proper altitude. Since the entire air traffic control system is very complex and is not required for an understanding of the present invention, only those portions required to present an environment for this invention will be described. In the particular system, as many as twenty-four aircraft are simultaneously handled and displayed on a single PPI scope. This invention provides the appropriate labeling of each aircraft displayed.

The air traffic control system incorporating this invention is illustrated in part in block diagram in FIG. 1, where there is shown a conventional PPI radar display including a cathode-ray tube 10 used for presenting indications in polar coordinates of reflected target returns from controlled aircraft. It is to be understood, of course, that any other data may also be presented, and this invention is not limited to aircraft. For example, the data may be a particular item on an assembly line, or trains in a large switching yard. The beam of the cathode-ray tube 10 is swept by conventional means angularly in synchronism with the radar antenna, and radially by a sawtooth voltage representing a predetermined range. Conveniently, the beam may be swept in azimuth by a conventional annular yoke 11 rotated in synchronism on the axis of the cathode-ray tube 10 through a gear 13 driven by the antenna. The range deflection is provided by the sawtooth output applied to the yoke 11 from a conventional range timer 15, the operation of which is initiated by the usual range trigger. The intensity of the beam is controlled by the target return signals applied to the control grid 14 from the radar receiver (not shown) to produce a plurality of data indications 12, i.e., indications of the aircraft targets.

70 The control grid 14 of the cathode-ray tube 10 is also controlled by the output from light-sensitive photo-

electric cell 16 which, as will be seen, yields an alphanumeric symbol and presents each symbol on the screen adjacent a particular data indication 12. It will be understood that the apparatus illustrated produces only the symbol A3 and that other essentially duplicate apparatus is required for producing the other illustrated symbols A1, A2, and A4.

The system for producing the alpha-numeric display symbol A3 comprises a conventional flying spot scanner which includes a cathode-ray tube 18 having a phosphorescent screen 20, a cathode 22, horizontal deflection plates 24, and vertical deflection plates 26. The beam of the cathode-ray tube 18 is swept rectilinearly, in a manner to be described, across the phosphorescent screen 20, and the beam of light which is produced on the screen 20 passes through a symbol mask 28. Preferably, the symbol mask 28 may consist of appropriate alpha-numeric or line drawings which are transparent in an opaque field and, for example, may take the form of a conventional photographic plate negative. The mask 28 is positioned between the flying spot scanner cathode-ray tube 18 and the photoelectric cell 16 to convert the transparent areas of the mask into electrical impulses. The electric impulses from the photocell are, in turn, used to control the intensity of the beam of the cathode-ray tube 10.

For the purpose of providing the rectilinear sweep for the beam of the flying spot scanner cathode-ray tube 18, the air traffic control system in which this invention was incorporated included a tracker for each aircraft under control. Each tracker provided the function of tracking a selected target and was provided with an electronic early-late gate which permitted the particular tracking unit to respond only to the selected target within a predetermined set of polar coordinates; and each tracker functioned to continuously report the changing position of the target in terms of direct voltages representing range and azimuth. That is to say, the tracker, in so far as this invention is concerned, serves the function of providing two voltages, one representing the instantaneous azimuth V_o and the other representing the instantaneous range V_R of the tracked aircraft. The details of the tracker form no part of this invention and, therefore, are not included in this description; and the tracker 30 illustrated simply in block form is represented as having a direct voltage output V_R representing range and V_o representing azimuth.

The voltages V_R and V_o are compared in magnitude with the sawtooth voltages $V_R(\text{ref})$ and $V_o(\text{ref})$ generated in Range and Azimuth sawtooth voltage generators 32 and 34, respectively. The sawtooth output from the range reference voltage generator 32 is initiated by the range trigger. The voltages $V_R(\text{ref})$ and $V_o(\text{ref})$ are synchronized with the deflection voltages of the cathode-ray tube 10. That is to say, the range reference sawtooth voltage $V_R(\text{ref})$ represents the range coordinate, while the azimuth reference sawtooth voltage $V_o(\text{ref})$ represents the angular coordinate of the beam on the screen of the cathode-ray tube 10. The system is designed so that when the beam of the cathode-ray tube 10 is in coincidence with the appropriate data indication 12, i.e., the indication adjacent symbol A3, the instantaneous values of voltages $V_o(\text{ref})$ and $V_R(\text{ref})$, respectively, equal the direct voltage outputs V_R and V_o from the tracker 30. For the purpose of determining when this instant of equality occurs, the voltages V_R and $V_R(\text{ref})$ are compared in a range comparator 36, a voltage spike 37 being produced in the output of the range comparator 36 when the voltages are equal. The voltage spike 37 is then applied to a range scanner trace generator 38. Similarly, the voltages V_o and $V_o(\text{ref})$ are compared in an azimuth comparator 40, a voltage spike 41 being produced and applied to an azimuth scanner trace generator 42 when equality exists.

The scanner trace generators 38 and 42 are described hereinafter in more detail. However, it should be noted

5 at this point that upon the occurrence of a voltage spike 41 at the input of the azimuth scanner trace generator 42, a sawtooth voltage 44 and a square wave voltage 46 are simultaneously produced at first and second output leads 45 and 47, respectively. When the voltage spike 37 is presented at one input of the range scanner trace generator 38 and also when the square wave voltage 46 is simultaneously applied at a second input, a sawtooth voltage 48 and a square wave voltage 50 are produced at output leads 49 and 51, respectively. Note that the range scanner trace generator 38 is so arranged that the occurrence of a voltage spike 37 will not render it operative in the absence of the square wave voltage 46 from the generator 42, an event which occurs only when there is coincidence in the azimuth coordinate. Thus, both generators 38 and 42 are rendered operative only upon the coincidence in both the azimuth and range coordinates.

10 The sawtooth output 44 of the azimuth scanner trace generator 42 is applied to the amplifier and phase splitter 54 and then to the vertical deflection plates 26 of the cathode-ray tube 10 to drive the beam vertically. Simultaneously, the square wave output 46 is applied to the generator 38 to start its operation. The square wave output 50 of generator 38 is then applied to the intensity 15 control grid 23 of the cathode-ray tube 18 to brighten the beam of the tube. In addition, the sawtooth voltage 48 is applied to the amplifier and phase splitter 52 and to the horizontal deflection plates 24 of the cathode-ray tube to deflect the now-brightened beam horizontally.

20 30 Since the range reference voltage $V_R(\text{ref})$ is in synchronism with the range sweep of the beam of the cathode-ray tube 10, it is apparent that a voltage spike 37 will result each time the voltage V_R equals $V_R(\text{ref})$, and that during the period that the square wave 46 is applied, a sawtooth voltage 48 will be repeatedly generated. Thus, for the duration of the square wave 46, the beam of the cathode-ray tube 18 will be horizontally swept each time the beam of the cathode-ray tube 10 is swept radially.

25 35 40 Thus, a rectilinear television type scan of the beam of the cathode-ray tube 18 is produced across the phosphorescent screen 20 immediately after each occurrence of coincidence of the beam of the cathode-ray tube 10 with the target return indication. Since the light produced on the phosphorescent screen 20 passes through the alpha-numeric mask 28, the photocell 16 is energized by light energy representing the particular alpha-numeric symbol A3, and this energy is synchronized with the range sweep of the cathode-ray tube 10. When the voltage output from the photocell 16 is applied to the intensity control grid 14 of the cathode-ray tube 10, the alpha-numeric symbol is presented on the screen of the cathode-ray tube 10 positioned immediately radially beyond the particular data indications 12 representing the 45 50 55 selected target being tracked by the tracker 30.

With a system constructed as thus far described, there are two undesirable conditions resulting which require correction; namely, the size of the symbols will change, depending on the distance of the data indication 12 from the center of the cathode-ray tube; and, further, with the mask 28 in a fixed position the alpha-numeric display will not be in constant rectitude. That is to say, if the alpha-numeric symbols are upright in one position on the screen of the cathode-ray tube 10, then they will be upside down when the target moves 180 degrees from that position.

60 65 70 75 The symbol size will not be constant without additional circuitry because of the nature of a PPI radar display. That is to say, in a PPI display the origin of the cathode-ray tube sweep represents the geographical location of the radar antenna, and the beam is then swept both radially and angularly. The radial sweep to the outer extremity of the cathode-ray tube is at a linear rate, and it provides a linear relationship between range and time,

and this sweep is repeated synchronously at the pulse repetition frequency rate of the radar transmitter. The angular position of the sweep is rotated in synchronism with the radar.

FIG. 2 illustrates the manner in which the symbol size will change without additional corrective circuitry. Remembering that the radial length l of any symbol is determined by the duration of the horizontal sweep applied to the beam of the cathode-ray tube 18, it will be seen that the dimension l is a function of the magnitude of the sawtooth wave 48. In the description below of the scanner trace generator 38, it will be shown that the magnitude of the sawtooth wave 48 is maintained constant, regardless of its duration. Therefore, the dimension l is maintained constant. It will also be recalled that the arcuate height h of the symbol area is determined by the duration of the sawtooth wave 44 and by the angular sweep of the beam of the cathode-ray tube 19. If the duration of the sawtooth wave 44 is maintained constant, then for any given angular sweep a point on the beam at a range R_1 will travel a greater distance h_1 than a point on the beam at a shorter range R_2 where only a distance h_2 is traversed. Thus, as may be seen by a comparison of the solid line symbol at range R_1 and the dotted line symbol at range R_2 , a change in size of the height dimension h will occur proportional to the range R of the target from the radar antenna, and this dimensional change in the symbol causes a serious aspect ratio ($1/h$) distortion for any symbol information.

In order to maintain a constant aspect ratio while simultaneously maintaining a constant size, the dimension h is made to vary inversely with range, and for this purpose we provide a symbol aspect ratio correction circuit 56 which will be described in detail below. As will be seen, the duration of the sawtooth voltage output 44 is adjusted in accordance with range (V_R) to provide a reduced duration vertical sweep for the cathode-ray tube 18 as the voltage V_R increases and an increased duration when V_R decreases. This results in a symbol presentation which will have a constant height h .

Because of the rotation of the beam of the PPI display, the symbols illustrated in FIG. 2 are not in proper rectitude, and it will be understood that proper rectitude can be established at only one target azimuth, namely, due east. To correct for this misalignment the symbol mask 28 is properly oriented for a given position and is then rotated synchronously with the radar antenna through gearing 60 in a direction counter to that of the PPI sweep rotation, or if more practical, the mask 28 may be driven by a servo motor synchronized with the rotation of the radar antenna by conventional servo practices.

The details of the scanner trace generators 38 and 42 and the symbol aspect ratio correction circuit 56 are shown in FIG. 3, to which reference is now made. It will be recalled that two outputs are required from each of the generators 38 and 42, one a square wave and the other a sawtooth wave. To produce these outputs we provide two essentially identical circuits differing primarily in parameters to provide the different time constants required.

The range scanner trace generator 38 comprises a triode V_1 having a plate 61, a grid 62, and a cathode 64, and a triode V_2 having a plate 66, a grid 68, and a cathode 70. The cathodes 64 and 70 are connected directly to ground while the plates 61 and 66 are connected to a B_+ supply through plate resistors 72 and 73, respectively. The plate 61 of triode V_1 is connected to the grid 68 of triode V_2 through condenser 74, and the plate 66 of triode V_2 is connected to the grid 62 of triode V_1 through parallel-connected condenser 76 and resistor 78. The grid 62 is connected to a B_- supply through a resistor 80. A diode 82 is connected between the grid 68 and ground. The condenser 74 is connected to a fixed direct current B_+ supply through a variable resistor 84 and a

70
75

fixed resistor 86. The grid 68 of triode V_2 is connected to the output lead 47 of the azimuth scanner trace generator 42 through a clamping diode 88. The square wave output 50 for brightening the beam of the cathode-ray tube 18 is derived from the plate 66 through a condenser 87. Input voltage spikes 37 are applied to the circuit through a diode 89.

The azimuth scanner trace generator 42 is essentially identical to that of the range scanner trace generator 38, and it comprises a triode V_3 having a plate 90, a grid 92, and a cathode 94, and a triode V_4 having a plate 96, a grid 98, and a cathode 100. The cathodes 94 and 100 are connected directly to ground while the plates 90 and 96 are connected to the B_+ supply through plate resistors 102 and 103, respectively. The plate 90 of triode V_3 is connected to the grid 98 of triode V_4 through a condenser 104, and the plate 96 of triode V_4 is connected to the grid 92 of the triode V_3 through parallel-connected condenser 106 and resistor 108, the grid 92 also being connected to a B_- supply through a resistor 110. A diode 112 is connected between the grid 98 and ground. The condenser 104 is connected to a large direct current supply through variable resistor 114 and fixed resistors 116 and 132. Unlike the generator 38, this direct voltage is automatically variable and is derived from the output lead 117 of the symbol aspect ratio correction circuit 56. Input voltage spikes 41 are coupled to the circuit from the range comparator through a diode 119.

Discussing first the operation of the azimuth scanner generator 42, initially (at time t_0 , FIG. 4) the triode V_4 is maintained at maximum conduction by the clamping of the grid 98 to ground potential by means of the diode 112. This results in a low voltage at the plate 96, and this voltage is not sufficient to overcome the cutoff bias from the B_- supply applied to the grid 92 of the triode V_3 . Therefore, the sawtooth voltage output 44 at lead 45 is maintained at zero and the square wave voltage output 46 at lead 47 is maintained at a negative level equal to the cutoff voltage applied to the grid 92.

Upon the occurrence of the negative voltage spike 41, the condenser 104 is charged through the diode 119, and the triode V_4 is rendered momentarily non-conductive. This results in a sudden increase of the voltage at the grid 92 of triode V_3 , thereby driving that triode into conduction. Conduction of triode V_3 results in the application of a decreased voltage from the plate 90 to the grid 98 of the triode V_4 , which is thereby driven into cutoff. When V_4 is cut off, V_3 is at maximum conduction, i.e., drawing grid current. Thus at t_1 the square wave voltage 46 at lead 47 is suddenly raised from a negative voltage to zero, and the sawtooth voltage 44 at lead 45 is reduced to cutoff grid bias potential of triode V_4 at a rate determined by the rate of discharge of condenser 104.

The charge on condenser 104 leaks off at a rate dependent on the time constants of condenser 104 and resistors 114 and 116 and on the magnitude of the voltage from the aspect ratio correction circuit 56. If resistors 114 and 116 are held fixed, this results in an output from lead 45 which is a sawtooth voltage having a duration dependent upon the voltage supplied from the aspect ratio correction circuit 56. When the charge leaks off condenser 104 at time t_2 , the triode V_4 returns to maximum conduction, and the triode V_3 is returned to cutoff. Thus, the output voltage on lead 47 is a square wave having an initial negative value and then, for a period of time t_1 to t_2 has a zero potential. The parameters are designed so that the negative value of the square wave 46 is sufficient to maintain the triode V_2 in the generator 38 at cutoff under all operating conditions.

Referring now to the scanner trace generator 38, it will be seen that at time t_0 the negative voltage applied through the lead 47 and the diode 88 to the grid 68 maintains triode V_2 at cutoff. The large resultant voltage on the plate 66 is applied to the grid 62 and is sufficient to overcome the negative cutoff bias applied from the B_- supply. Therefore, triode V_1 is initially in maximum

conduction, that is, drawing grid current, while triode V_2 is maintained in cutoff.

Since the cutoff bias provided at lead 47 through the diode 88 is sufficient to maintain the triode V_2 cutoff at all times, receipt of a voltage spike 37 will not change the status of the triodes until this bias is removed. Upon removal of the cutoff bias from the grid 68, the triode V_2 is rendered conductive and the triode V_1 is cut off. Operation then results in a manner similar to that of the generator 42, that is, receipt of voltage spikes 37 will cause the triodes to change state. The voltage charge developed across condenser 74 by a subsequent voltage spike 37 leaks off through resistors 84 and 86 and, hence, a sawtooth voltage 48 is produced at the output lead 49 having a duration fixed by the circuit time constants. It will be noted that the maximum and minimum values of the sawtooth wave will be fixed, irrespective of the duration of the wave. This is because the maximum and minimum values are determined by the voltages on the grid 68 of triode V_2 when it is cut off, and again when it is at maximum conduction. Since these two values are predetermined by tube characteristics and circuit design, the sawtooth voltage will have a constant amplitude and, hence, the length l of the displayed symbol will be maintained constant on the screen of the cathode-ray tube.

In order to maintain the height dimension h of the symbol constant, the duration of the sawtooth wave 44 applied to the deflection plates 24 is varied in inverse proportion to the voltage V_R . This is accomplished by the aspect ratio correction circuit 56 which provides a variable voltage for one plate of the condenser 104.

The circuit 56 includes a first triode V_5 having a plate 122 connected to a $B+$ supply, a grid 124 connected to the V_R output of the tracker 30, and a cathode 126 connected to ground through a cathode resistor 128. A second triode V_6 having a plate 130 connected to the $B+$ supply through a resistor 132 and a grounded grid 134 is provided with a variable voltage directly proportional to V_R at its cathode 136 from cathode resistor 128 through a movable tap 138. In operation of the correction circuit 56, an increasing voltage V_R applied to the grid 124 produces increased conduction through the triode V_5 and, therefore, develops an increased voltage across the resistor 128 and on the cathode 136 of triode V_6 . The increased voltage which results on the plate 130 is applied through the lead 117 to one plate of the condenser 104 in the azimuth scanner trace generator 42.

Since the duration of the sawtooth wave 44 is a function of the R.C. time constants and the voltage difference between the plates of the condenser 104, it is evident that the duration of the sawtooth wave will be a function of the voltage E on one plate, if the voltage on the other plate is maintained constant. Mathematically, this relationship is defined as $T = 1n E$, where T is the duration of sawtooth wave 44 and E is the voltage at lead 117. Since at small angles the natural logs ($1n$) are approximately equal to tangents, then referring to FIG. 4, h , which is a function of θ , may be varied in accordance with the equation: $1n E = \tan^{-1} h/R \approx \theta$. It is clear, therefore, that an increase in the value of V_R will decrease the length of the sawtooth wave, thereby maintaining the dimension h of the symbol constant.

While in most instances the mask 28 illustrated in FIG. 1 may be adequate for identification of the particular data, in some applications it may be desirable to use a mask such as illustrated in FIG. 5. This mask is comprised of two portions consisting of a disk 150 and a tangentially positioned plate 152, both the disk and the plate having translucent symbols on an opaque background.

In the particular embodiment illustrated in FIG. 5, the symbols on the plate 152, in conjunction with the numerals on the rotatable disk 150, are extremely useful in an air traffic control system. For example, the symbols on the plate 152 might be used to designate the particular target, and whether or not the target is late, early, or on

time. That is to say, the symbol A might identify the aircraft while AE and AL give "early" and "late" indications. The numerals on the disk 150 might indicate altitude or range.

5 The point of contact between the disk 150 and the plate 152 is positioned in front of a cathode-ray tube 154 similar to the tube 18 in FIG. 2. In this embodiment, however, the cathode-ray tube is mounted in a ring gear 156, and the entire tube 154 is rotated on its axis by a drive connection from the radar antenna through gearing 158. This 10 rotation is counter to the rotation of the PPI scope azimuth scan and serves the purpose of maintaining proper rectitude of the symbol. The mask 152 may be driven by an appropriate servo motor so as to position the appropriate on-time early or late symbol (A, AE or AL) at the point of contact; and similarly, the mask 152 may be driven by another servo motor in response to the range, 15 altitude, or other information relative to the target. The light passing through the mask is directed toward the 20 photocell 16.

Having thus described this invention, what is claimed is:

1. In a cathode-ray tube display system wherein a data indication is presented on the screen of a cathode-ray display tube by brightening the beam of said tube at a controlled time, said beam being deflected radially at a high rate and angularly at a relatively low rate, and means are 25 provided for presenting a symbol on said screen adjacent said data indication for identifying said data indication, the combination comprising: a light sensitive device for producing a voltage output in response to light energy, said voltage output being coupled to said cathode-ray display tube to control the brightness of the beam of said tube; a cathode-ray scanner tube having a phosphorescent screen and horizontal and vertical deflection means; a mask comprised of opaque and translucent portions having a pattern representing said symbol, said mask being interposed between the screen of said cathode-ray scanner tube and said light sensitive device; means for relatively rotating said mask and said screen in synchronism with said angular deflection in the direction counter thereto; means for rectilinearly sweeping the beam of said cathode-ray scanner tube across said mask, said means including a first generator having a first sawtooth voltage output coupled to one of said deflection means, and a second generator having a second sawtooth voltage output coupled to the other of said deflection means, said second sawtooth voltage output being synchronized with the radial deflection of the beam of said cathode-ray display tube in one dimension; and means for initiating operation of said generators at said controlled time whereby said beam of said display tube is brightened in accordance with said pattern and said symbol is presented on the screen of said cathode-ray display tube adjacent said indication.

2. The invention as defined in claim 1, wherein means 55 are provided for regulating the duration of the sawtooth voltage output of said first generator in inverse proportion to the radial distance of said data indication from the origin of the beam on the screen of said cathode-ray display tube.

3. The invention as defined in claim 2 wherein said second generator is rendered inoperative except for the period of duration of said sawtooth voltage of said first generator.

4. In a radar system for presenting a reflected target signal as an indication on the screen of a PPI cathode-ray display tube, said tube having beam deflection means and beam brightening means, said beam being deflected radially at a high rate and angularly at a relatively low rate, the radial deflection being a function of range, and the angular deflection being a function of azimuth, and means for presenting an identification symbol on said screen adjacent said indication, the combination comprising: means for producing a first direct voltage which is a function of the range of said target; a range reference voltage source for generating a first sawtooth voltage hav-

ing a magnitude which is a function of range; means for comparing said first direct voltage with said first sawtooth voltage and for producing a range coincidence pulse when said voltages are equal; means for producing a second direct voltage which is a function of the azimuth of said target; an azimuth reference voltage source for generating a second sawtooth voltage having a magnitude which is a function of azimuth; means for comparing said second direct voltage with said second sawtooth voltage for producing an azimuth coincidence pulse when said second direct voltage and said second sawtooth voltage are equal; a flying spot scanner comprising a cathode ray scanner tube having a phosphorescent screen, horizontal and vertical deflection plates, a range scanner trace generator for generating a sawtooth voltage output for energizing said horizontal deflection plates for horizontally deflecting the beam of said scanner tube, an azimuth scanner trace generator for generating a sawtooth voltage output for energizing said vertical deflection plates for vertically deflecting the beam of said scanner tube, operation of said range and azimuth scanner trace generators being initiated by said range and azimuth coincidence pulses respectively, said range scanner trace generator being biased for non-operation except for the period of duration of the sawtooth voltage output of said azimuth scanner trace generator; a light sensitive device; a mask interposed between the screen of said scanner tube and said device, said mask comprising opaque and translucent portions having a pattern representing said symbol, the output from said light sensitive device being coupled to said beam brightening means of said display tube, the radial deflection of the beam of said display tube being synchronized with the sawtooth voltage of said range reference voltage.

5. The invention as defined in claim 4 wherein the duration of each sawtooth voltage wave generated by said azimuth scanner trace generator varies in inverse proportion to the range of said target, whereby the arcuate length of said symbol is maintained constant.

6. The invention as defined in claim 5 wherein the minimum and maximum magnitude of the sawtooth voltage generated by said range scanner trace generator is maintained constant, whereby the radial length of said symbol is maintained constant.

7. The invention as defined in claim 4 wherein said mask and said scanner tube are relatively rotated in synchronism with the angular deflection of the beam of said display tube in a resultant direction counter thereto.

8. The invention as defined in claim 4 wherein said mask comprises a disk rotatable on an axis, and a plate tangentially movable at the periphery of said disk, the point of contact of said plate and disk being positioned in the path of said beam of light between said screen and said device, the patterns of said plate and disk representing a plurality of symbols which may be selectively positioned in said path.

9. A sawtooth generator comprising: first and second triodes each having a plate, a grid, and a cathode, said cathodes being connected to a point of reference potential and each of said plates being connected to a source of direct voltage through a plate resistor; a connection from the plate of said first triode to the grid of said second triode through a first condenser; a connection from the plate of said second triode to the grid of said first triode through a second condenser; a leakage path for said first condenser connected from a point of positive potential to the junction of said first condenser and the grid of said second triode; a diode connecting the grid of said second triode to said point of reference potential, said diode being poled for conduction from the grid of said second triode to said point of reference potential, and a source of negative cut-off potential applied to the grid of said first triode through a resistor, whereby said second triode is at maximum conduction and said first triode is cut off; means applying a voltage pulse to the plate of said first triode to render said first triode conductive at a maximum level

and to cut off said second triode; and means for deriving a sawtooth output voltage from said junction, the magnitude of said sawtooth voltage output being constant between limits determined by the grid voltage of said second triode at maximum conduction and at cut-off.

5. 10. The invention as defined in claim 9 wherein said point of positive potential is automatically variable in accordance with a function, and the duration of said sawtooth voltage output is variable in inverse proportion to the voltage at said point of positive potential.

10. 11. In a cathode-ray tube display system wherein a data indication is presented on the screen of a cathode-ray display tube by brightening the beam of said tube at a controlled time, said beam being deflected at a high rate in one dimension and at a relatively low rate in a second dimension, and means are provided for presenting a symbol on said screen adjacent said data indication for identifying said data indication, the combination comprising: a light sensitive device for producing a voltage output in response to light energy, said voltage output being coupled to said cathode-ray display tube to control the brightness of the beam of said tube; a cathode-ray scanner tube having a phosphorescent screen and horizontal and vertical deflection means; a mask comprised of opaque and translucent portions having a pattern representing said symbol, said mask being interposed between the screen of said cathode-ray scanner tube and said light sensitive device, said mask comprising a disk rotatable on an axis, and a plate tangentially movable at the periphery of said disk, the point of contact of said plate and disk being positioned in the path of said beam of light between said screen and said device, the patterns of said plate and disk representing a plurality of symbols which may be selectively positioned in said path; means for rectilinearly sweeping the beam of said cathode-ray scanner tube across said mask, said means including a first generator having a first sawtooth voltage output coupled to one of said deflection means, and a second generator having a second sawtooth voltage output coupled to the other of said deflection means, said second sawtooth voltage output being synchronized with the deflection of the beam of said cathode-ray display tube in one dimension; and means for initiating operation of said generators at said controlled time whereby said beam of said display tube is brightened in accordance with said pattern and said symbol is presented on the screen of said cathode-ray tube display adjacent said indication.

15. 12. The combination comprising: a cathode-ray display tube having a phosphorescent screen, deflection means for sweeping the beam of said cathode-ray display tube over said screen in two dimensions, said dimensions being radial and angular, and intensity control means for said beam; a beam of radiant energy; a radiant energy sensitive device for producing an output responsive to the

20. 25. intensity of said beam of radiant energy intercepted thereby, said output being applied to said intensity control means of said cathode-ray display tube; a medium having a radiation transmission characteristic pattern, said pattern representing a symbol, said medium being interposed between said beam of radiant energy and said radiant energy sensitive device; first means for sweeping said beam of radiant energy over said medium in one dimension; second means for sweeping said beam of radiant energy over said medium in a second dimension, the

30. 35. sweeping of said beam of radiant energy in one dimension being synchronized with the radial sweeping of the beam of said cathode-ray display tube; means for initiating the sweep of said beam of radiant energy over said medium at selected times; and means for relatively rotating the orientation of the sweep of said beam of radiant energy with respect to said medium in a direction opposite to the angular sweep of the beam of said cathode-ray display tube.

35. 40. 13. The invention as defined in claim 12 wherein said first means for sweeping said beam of radiant energy is

45. 50. 55. 60. 65. 70. 75.

inoperative except when said second means for sweeping said beam of radiant energy is operative.

14. The invention as defined in claim 12 wherein said means for relatively rotating said orientation comprises means for mechanically rotating said medium in a direction opposite to the angular sweeping of the beam of said cathode-ray display tube.

15. In a system for displaying the plan position of a moving target in radial and angular coordinates, said system including a cathode-ray display tube, the beam of which is deflected radially at a relatively high rate as a function of range and angularly at a relatively slow rate as a function of azimuth, and modulating means for modulating said beam to produce a moving indication of the position of said target in said coordinates on the screen of said display tube, the combination including means for superimposing a symbol on said screen continuously adjacent said moving indication, said means for superimposing a symbol comprising: a beam of radiant energy; a radiant energy sensitive device for developing an output voltage in response to radiant energy intercepted thereby, said output voltage being coupled to said modulating means for further modulating said beam of said display tube; a medium having a radiation transmission characteristic pattern, said pattern representing a symbol, said medium being interposed between said beam of radiant energy and said radiant energy sensitive device; means for scanning said medium with said beam of radiant energy to sensitize said device in accordance with the scanned pattern of said medium, said scanning means including first and second generators for generating first and second deflection voltages for deflecting said beam of radiant energy in first and second coordinates, said first generator being synchronized with the radial deflection of said display tube; means responsive to coincidence of the beam of said display tube with the angular positioned coordinate of said target indication for rendering said second generator operative for generating said second deflection voltage for deflecting said beam of radiant energy in said second coordinate; and means responsive to the coincidence of the beam of said display tube with the radial position coordinate of said target indication and to the generation of said second deflection voltage for successively rendering said first generator operative to successively generate said first deflection voltage for deflecting said beam of radiant energy in said one coordinate, said first generator being inoperative in the absence of said second deflection voltage output from said second generator, whereby the beam of said display tube is modulated in accordance with said pattern and said symbol is superimposed on said display tube at a position continuously adjacent said target indication.

16. The invention as defined in claim 15, and means for relatively rotating the orientation of the deflection of said beam of radiant energy with respect to said medium in a direction opposite to the angular deflection of the beam

of said display tube, whereby said symbol is maintained in proper rectitude.

17. The invention as defined in claim 16 wherein said first and second coordinates are rectilinear.

18. The invention as defined in claim 17 wherein said means for relatively rotating said orientation comprises means for mechanically rotating said medium in a direction opposite to the angular deflection of the beam of said display tube.

19. In a cathode-ray tube display system wherein a data indication is presented on the screen of a cathode-ray display tube by brightening the beam of said tube at a controlled time, said beam being deflected at a high rate in one dimension and at a relatively low rate in a second dimension, and means are provided for presenting a symbol on said screen adjacent said data indication for identifying said data indication, the combination comprising: a light sensitive device for producing a voltage output in response to light energy, said voltage output being coupled

20 to said cathode-ray display tube to control the brightness of the beam of said tube; a cathode-ray scanner tube having a phosphorescent screen and horizontal and vertical deflection means; a mask comprised of opaque and translucent portions having a pattern representing said symbol, said mask being interposed between the screen of said cathode-ray scanner tube and said light sensitive device; means for rectilinearly sweeping the beam of said cathode-ray scanner tube over said mask, said means including a first generator having a first sawtooth voltage output coupled to one of said deflection means, and a second generator having a second sawtooth voltage output coupled to the other of said deflecting means, said second sawtooth voltage output being synchronized with the deflection of the beam of said cathode-ray display tube in

30 one dimension; means for regulating the duration of the sawtooth voltage output of said first generator in inverse proportion to the distance of said data indication from the origin of the sweep in said one dimension over the screen of said cathode-ray display tube; and means for 35 initiating operation of said generators at said controlled time, said second generator being rendered inoperative except for the period of duration of said sawtooth voltage of said first generator, whereby said beam of said display tube is brightened in accordance with said pattern and said symbol is presented on the screen of said cathode-ray display tube adjacent said indication.
